(57) **CLAIM**

The ornamental design for a shaft for driven let-off stand in
a tire bead winding assembly, as shown and described.

DESCRIPTION

FIG. 1 is a perspective view of my new design of a shaft for
a driven let-off stand in a tire bead winding assembly;
FIG. 2 is a front elevation view thereof;
FIG. 3 is a rear-elevation view thereof;
FIG. 4 is a top plan view thereof;
FIG. 5 is a bottom plan view thereof;
FIG. 6 is a left side elevation view thereof;
FIG. 7 is a right side elevation view thereof; and,
FIG. 8 is a perspective view of the present shaft design in
relation to a driven let-off stand which is shown in phantom
lines for illustrative and environmental purposes only.
